GASEOUS ELECTRIC DISCHARGE DEVICE

Marcello Pirani, Berlin-Wilmersdorf, and Martin Reger, Berlin, Germany, assignors to General Electric Company, a corporation of New York

Application February 10, 1932, Serial No. 592,136,
and in Germany February 14, 1931

3 Claims. (Cl. 176—124)

The present invention relates to gaseous electric discharge devices generally and more particularly the invention relates to such devices the gaseous filling of which is a mixture of gases, or a 5 gas and a metal vapor and which operate on direct current.

We have observed that the gaseous mixture in a gaseous electric discharge device operating on direct current has a tendency to separate into its 10 various gaseous constituents under the influence of the electric discharge in said device, the more electro-positive constituent travelling toward the cathode. This phenomena is accompanied by a change in the color of the light emitted by the 15 electric discharge device; that is, the color of the emitted light changes from that of the gas mixture at all parts of the container of said device to that of the various gas constituents at different parts of the device. This separation or "de-mixing" of the gas mixture with the accompanying 20 change in the color of the light emitted by said device is noticeable after a comparatively short period of operation, in the order of six hours, for example, and becomes more pronounced during 25 each operating period since the mixture of the gases is only partly reestablished during the period that the device is not in operation. The object of this invention is to control the separation 30 of the gas mixture in a gaseous electric discharge device operating on direct current to such extent that there is no noticeable change in the color of the light emitted by the gas mixture in said device. Another object of the invention is to accomplish this result by means external to said 35 device. A further object of the invention is to provide a simple switch connected into the circuit of said device for reversing the polarity of the current applied to the electrodes of said device. Still further objects and advantages attaching to 40 the invention and to its use and operation will be apparent to those skilled in the art from the following particular description and from the appended claims.

In accordance with this object the invention 45 comprises the method of and a means for reversing the polarity of an electric discharge device operating on direct current at time intervals less than that time interval required for the separation of the gas mixture in said device to noticeably 50 affect the light emitted by said gas mixture. This separation of the gas mixture takes place gradually and does not become noticeable until the device has been operating for approximately six hours; therefore in the ordinary use of the 55 lamp it is sufficient that the polarity be reversed

manually each time the device is placed into operation since a lamp used for illuminating purposes is rarely in operation more than six hours. This reversal in polarity which occurs the second time the lamp is placed into operation causes the 60 more electro-positive gaseous constituent to travel in the opposite direction from that in which it travelled in the first operating period which causes first, a thorough mixing of the various constituents of the gas mixture to overcome the separation thereof which took place in the first operating period and then a gradual separation of the gas mixture as in the first operating period so that the time required for the separation of the gases of the gas mixture to noticeably affect the color of the light emitted by said device is approximately twice as long in the second operating period than in the first. This phenomena which occurs the second time the device is placed into operation takes place each time thereafter that the polarity of the current applied to the electrodes of the device is reversed. 75

The switch for reversing the polarity of the current applied to the electrodes of the electric discharge device consists of two electrically conducting ring members electrically insulated from each other and rigidly attached to each other physically. Each of said ring parts is electrically connected permanently to one of the electrodes of the electric discharge device and is adapted to 80 make electrical connection with one terminal of a direct current source. The switch is so constructed that when the ring parts are turned 180° from their original position each of said ring parts is connected to the opposite terminal 85 of said current source so that the polarity of the current on said device is reversed; when the switch is turned 90° from either of these two positions the electric discharge device does not operate since both rings are in electrical connection 90 with a single terminal of the direct current source. 95

In the drawing accompanying and forming part of this specification an embodiment of our invention is shown schematically; in which, 100

Fig. 1 is a schematic representation of a gaseous electric discharge device and a circuit therefor the novel switch being shown in an operating position,

Fig. 2 is a similar view of the device the switch 105 being shown in an intermediate position,

Fig. 3 is the same as Fig. 1 the switch being shown in a different operating position and in which position the polarity of the current on said device is reversed, 110

Fig. 4 is a similar view of the new and novel switch in another intermediate position, and

Fig. 5 is a front elevational view of the switch.

Like numbers denote like parts in all views of 5 the device.

Referring to the drawing the electric discharge device 1 is filled with a mixture of gases or a mixture of gas and a vapor, such as a mixture of helium and argon, or a mixture of helium 10 and mercury vapor. Said device 1 has at each end thereof an electrode 2 and 3 which may be of any conventional type. Said electrode 2 is connected by lead 7 to electrically conducting part 5 of the new and novel polarity reversing 15 switch while electrode 3 is connected by lead 8, containing ballast resistance 9, to electrically conducting part 6 of said switch. Said parts 5 and 6 are electrically insulated from each other, but are rigidly attached to each other as shown 20 in the drawing. Each of said parts 5 and 6 have laterally extending contact arms 10 and 11 respectively which are at an angle of approximately 90° to each other and are adapted to make contact with contact segments 12, 13 as shown 25 in Fig. 1. Said contact segments 12, 13 are connected by leads 14, 15 respectively to the terminals of a source of direct current.

In its first position, shown in Fig. 1, electrode 2 is connected to the negative terminal of the 30 direct current source through lead 7, ring part 5, contact arm 10, contact segment 12 and lead 14 while electrode 3 is connected to the positive terminal of the direct current source by lead 8, ring part 6, contact arm 11, contact segment 13 35 and lead 15. If the switch is turned by handle 4 through 90° both contact arms 10 and 11 make contact with only one contact segment 12, as shown in Fig. 2, the electric discharge device in this position of said switch is inoperative since 40 both electrodes 2, 3 are then connected to the negative terminal of the direct current source. Another movement of handle 4 through 90° brings contact arm 10 into contact with contact segment 13 and contact arm 11 into contact segment 12, as shown in Fig. 3, so that the polarity 45 of the current on said electrodes 2 and 3 is the reverse of that on said electrodes when the switch is in that position shown in Fig. 1. Another 90° turn of handle 4 makes the device 1 inoperative 50 since both electrodes are connected to the posi-

tive terminal of the current source as shown in Fig. 4. A similar turn brings the switch to that position shown in Fig. 1. If desired a timing device such as a clock may be adapted to turn handle 4 through 180° to change the polarity on said device 1 at time intervals less than that time interval required for the separation of the gaseous mixture to affect the color of the light emitted by said device.

While we have shown and described and have pointed out various novel features of our invention it will be understood of course that various substitutions, modifications and changes in the form and details thereof and in its use and operation may be made by those skilled in the art without departure from the broad spirit and scope of the invention.

What we claim as new and desire to secure by Letters Patent of the United States is:—

1. The method of operating an electric discharge device comprising a container, a mixture of gases therein, electrodes sealed therein, said electrodes being connected to the terminals of a direct current source, which consists in changing the polarity of the current applied to said 100 electrodes at time intervals less than that time interval required for the separation of the gas mixture to noticeably affect the color of the light emitted by the gas mixture in said device.

2. In combination, an electric discharge device 105 comprising a container, a mixture of gases therein, electrodes sealed therein, said electrodes being connected to the terminals of a direct current source, and a switch interposed between said source and said device for changing the polarity 110 of the current applied to said electrodes whereby separation of the gas mixture is avoided.

3. In combination, an electric discharge device comprising a container, a mixture of gases therein, electrodes sealed therein, said electrodes being 115 connected to the terminals of a direct current source, and a switch interposed between said source and said device for changing the polarity 120 of the current applied to said electrodes at time intervals less than that time interval required for the separation of the gas mixture to noticeably affect the color of the light emitted by the gas mixture in said device.
